[57] CLAIM

The ornamental design for a beach safe, as shown and described.

DESCRIPTION

FIG. 1 is a front elevation view of a beach safe showing my new design;

FIG. 2 is a back elevation view of the beach safe shown in FIG. 1;

FIG. 3 is a top plan view of the beach safe shown in FIG. 1;

FIG. 4 is a left-side elevation view of the beach safe shown in FIG. 1; and,

FIG. 5 is a right-side elevation view of the beach safe shown in FIG. 1.

The broken line showing of the ground is for illustrative purposes only and forms no part of the claimed design.
